UNITED STATES PATENT OFFICE.

CHARLES I. LENIG, OF DANVILLE, PENNSYLVANIA.

DUST AND CINDER TRAP.

Application filed May 10, 1923. Serial No. 638,031.

To all whom it may concern:

Be it known that I, CHARLES I. LENIG, a citizen of the United States, residing at Danville, in the county of Montour and State of Pennsylvania, have invented a new and useful Dust and Cinder Trap, of which the following is a specification.

This invention relates to a dust and cinder trap adapted to be attached to the side of a railway car, or other swiftly moving vehicle.

The object of the invention is to provide a device of this kind which may be attached so as to extend between the windows on the side of a car, or other vehicle, in such a manner that the dust and cinders are trapped and conducted to the end of the car, so that they are prevented from entering the windows when the latter are open. Provision is also made for reversing the action of the air currents through the device, so as to adapt the same for the movement of the car in either direction. The attachment is so arranged that the cinders and dust, which would otherwise have a tendency to enter the windows when the latter are open, will be deflected to one side thereof without interfering with the ventilation of the car or obstructing the view from the windows.

The principles of the invention and the details of the construction, by means of which it is carried out, will be more clearly described in connection with the accompanying drawings, which illustrate the preferred form thereof.

In the drawings:

Figure 1 is a side elevation of a portion of a railway car having the invention installed thereon.

Figure 2 is a plan view of the invention.

Figure 3 is an enlarged perspective view of a portion of the trap, showing the relation of the conduits and gutters thereto.

Figure 4 is a horizontal sectional view through the trap.

Figure 5 is a view similar to Figure 4, but with the damper in a different position.

Figure 6 is a view, partly in elevation and partly in section, of the upper end of the trap.

Figure 7 is a vertical transverse section on the line 7-7 of Figure 4.

Figure 8 is a sectional view of the lower end of the trap, taken on the line 8-8 of Figure 7.

The invention, as shown, is attached to

the side of a railway car 10, and consists of a series of traps 11 disposed vertically between the windows of the car and connected at the top and bottom by conduits 12, which extend to the end of the car where they may be connected by a pipe 13 leading to a convenient point near the ground, where the cinders and dust collected by the traps may be discharged, without causing any annoyance to the passengers.

Each of the traps comprises a flat side 14 adapted to rest against the side of the car, and having at the top and bottom substantially semi-cylindrical bands 15 and 16, respectively, which are held in spaced relation by vertical spaced strips 17 and 18. The bands 15 and 16 are extended over the ends of the trap to form caps 19 and 20. Secured to the inner faces of these caps are inwardly extending flanges 21 and 22 concentric with the bands 15 and 16 and spaced therefrom to form guideways 23 and 24, which slidably receive the ends of the curved damper 25. The latter is in the shape of a cylindrical segment extending through an arc of approximately 120°, so that, as shown in Figures 3, 4 and 5, it may be adjusted to close one side of the trap while the other side is left open. A suitable wing or vane 26 may be secured centrally of the outer surface of the damper 25 and is moved between the upright strips 17 and 18 for the purpose of adjusting the damper.

Each of the conduits 12, above referred to, which connect the upper and lower ends respectively of the traps 11, includes a tubular section 27 and a gutter section 28. The corners of the damper are cut away, as shown at 29, so that the ends of the tubular sections are always open, while the ends of the gutter sections may be selectively closed by the damper together with the adjacent side of the trap. The tubular sections 27 serve to conduct the cinders or dust received through the open side of the trap, while the gutter serves to conduct the dust which enters through the longitudinal opening 30, between the edge of the gutter and the tubular section, into the trap.

In Figures 3 and 4 the damper is turned to the left, this being the proper position for trapping the cinders and dust when the vehicle is moving toward the right. In this position the cinders and dust entering through the longitudinal opening 30, be-

2
tween the tubular portion 27 and side of the gutter 28, pass along the gutter into the trap 11, while the opening 31 in the front side of the trap serves to trap all cinders passing 5 the sides of the windows. The cinders which are thus trapped will be conducted through the tubular sections 27 and the successive traps until they reach the downwardly extending discharge portion 13 of 10 the conduit, whence they will be discharged near the ground and out of the way. The eddies set up by the open sides of the traps 11 and the open sides of the gutters 28 will be sufficient to cause the deflection of cinders 15 and dust particles from the air, and the size of the tubular portions 27 and the conduits will be ample to permit the same to be conducted away, while there will be no appreciable interference with the air currents to 20 prevent the same from ventilating the interior of the car.

While I have shown and described specifically the structural details of one form in which my invention may be embodied, it is 25 to be understood that this is merely illustrative, and that various modifications may be made therein, as long as such modifications mark no material departure from the scope of the invention as claimed.

30 What is claimed is:

1. An attachment for railway cars and the like, comprising a trap having top and bottom caps spaced apart and provided with transverse curved guideways, a curved 35 damper extending from top to bottom of the trap and slideable in said guideways to open either side of the trap while closing the other side, and a conduit leading from the trap for conducting the intercepted particles to the end of the car.

2. An attachment for railway cars and the like, comprising a plurality of traps adapted to be attached between the side windows of the car, each trap having top 45 and bottom caps and provided with transverse curved guideways, a curved damper extending from top to bottom of the trap and operable to open either side of the trap while closing the other side, conduits connecting the traps to each other and leading

to the end of the car, and gutters adjacent the conduits and opening into the respective traps, said damper being extended so as to open and close the ends of the respective gutters, and being cut away so as to leave 55 the ends of the conduits always open.

3. The combination with a vehicle having side windows, of a series of dust and cinder traps adjacent the sides of the windows, each of said traps being hollow and substantially semi-circular in cross section, conduits connecting the traps and leading to the ends of the car, and slideable means for closing either side of the trap and at the same time opening the other side. 60

4. The combination with a vehicle having side windows, of a series of dust and cinder traps, one being adjacent the side of each window, said traps being hollow and substantially semi-circular in cross section, conduits connecting the traps and leading to the ends of the car, open gutters adjacent the conduits between the traps and opening into the interior of the traps, and a slideable damper for each trap operable to close 70 either side of the same while at the same time opening the other side.

5. The combination with a vehicle having side windows, of a series of dust and cinder traps adjacent the sides of the windows, each 80 of said traps being hollow and substantially semi-circular in cross section, conduits connecting the traps to each other at the top and bottom respectively and leading to the ends of the car, gutters adjacent the conduits 85 between the traps, the upper and lower gutters having their open sides facing away from each other, and a slideable damper for each trap operable to close either side of the same and the adjacent ends of the gutters 90 while at the same time opening the opposite side of the trap and the ends of the gutters adjacent thereto, the corners of the dampers being cut away sufficiently to leave the conduits always open. 95

In testimony that I claim the foregoing as my own, I have hereto affixed my signature.

CHARLES I. LENIG.
